UNITED STATES PATENT OFFICE.

CHRISTIAN H. MARTIN, OF COLUMBUS, OHIO, ASSIGNOR TO JOHN R. GAMMETER, OF AKRON, OHIO.

PIANO-BENCH.

1,269,948.

Specification of Letters Patent. Patented June 18, 1918.

Application filed June 30, 1916. Serial No. 106,920.

To all whom it may concern:

Be it known that I, CHRISTIAN H. MARTIN, a citizen of the United States, residing at Columbus, in the county of Franklin and 5 State of Ohio, have invented certain new and useful Improvements in Piano-Benches, of which the following is a specification.

This invention relates to a piano or organ bench where the main object resides in the provision of a structure whereby the bench may readily be transformed from what is commonly known as a lower horizontal position to an upper inclined position. The advantage of this structure is that manual playing of the instrument may be more 10 readily accomplished by having the seat in its lower position whereas the same is true of the upper inclined position for the treadle operation.

20 One of the main features of the present invention resides in the provision of a set of wings transversely arranged across the body support in such relation with the hinged seat of the body that this seat may 25 be conveniently and easily adjusted from its lower horizontal to its upper inclined position.

Still a further object of the invention resides in the provision of a structure whereby 30 the elevation of the wings to cause a corresponding adjustment of the seat may be automatically accomplished by the elevation of the seat itself. This structure may also 35 be supplemented by an arrangement where by the wings may also be automatically lowered upon the elevation of the seat after it has assumed its upper inclined position.

In addition to the above, my invention 40 also consists in the combination of the wings already referred to with a double back rail structure wherein one is movable with the seat as the seat itself moves from its lower to its upper position. By this arrangement, the appearance of the rear portion of the 45 seat is maintained for either position of the seat.

Other objects of my invention will become more apparent after a further detailed description of the accompanying sheets of 50 drawings wherein similar characters of reference designate corresponding parts and wherein,

Figure 1 is a view in perspective of a piano bench embodying the principles of 55 my invention,

Fig. 2 is a transverse section taken through the bench with the lid in its elevated position and with the back rail in its lower position, all as represented on line 2-2, Fig. 5;

60 Fig. 3 is a transverse section showing the wing structure in its lower position as represented by line 3-3 of Fig. 5 but showing the lid in its lower position,

Fig. 4 is a view taken similarly to Fig. 2 but showing the lid in its lowered position,

Fig. 5 is a top plan view of the bench structure showing the lid in its elevated position,

Fig. 6 is an enlarged sectional detail taken 70 through hinge and back rail structure showing the back rail in its lower position with the lid elevated, and,

Fig. 7 is a similar section showing back rail in its upper position with the lid low- 75 ered.

In these several views, the bench is shown as comprising end pieces, 1, held spaced by means of the front rail, 2, and a double back rail consisting of a stationary member 3 and a movable member 4. The bottom, 5, may span the distance between the rails, 2 and 3, and in this manner a compartment is formed. To the movable back rail, 4, there is hingedly mounted as is shown at 6, a seat 7 which 80 seat member is capable of assuming a horizontal or an upper inclined position as will now be described.

Transversely spanning the distance between the front and back rails, 2 and 3, and adjacent the end pieces, 1, are rods, 8, upon each of which a wing, 9, is rotatably mounted. These wings are provided with an inclined top face, 10, as is shown and by means of their rotatable mounting may be made to 90 assume a horizontal position as is shown in Fig. 3, being limited against further movement by means of a stop ledge shown at 11, and a vertical position as is shown in each of Figs. 2 and 4.

100 After the lid, 7, has been elevated to the position as shown in Fig. 2, these wings may be made to assume a vertical position and upon again lowering the lid, this lid will fulcrum about the points, 12, as indicated in Fig. 2 to cause an elevation of the movable rail, 4, as the lid continues in its downward movement. In order to accommodate this vertical movement of the rail, 4, I have resorted to the use of a special hinge construc- 110

tion shown in detail in Figs. 6 and 7. The lower wing, 13, of each of these hinges is made wider than is necessary in order to overhang the inside edge of the movable rail, 4. In fact, these wings, 13, are preferably made wide enough to cover the top edges of both the back rails, 3 and 4. The stationary rail, 3, is socketed at the point where each hinge occurs and these sockets 5 are each provided with a bushing or tubular member shown at 14. Within each bushing, there is slidably mounted a stem shown at 15, each stem being rigidly attached to the overhanging portion of the wings, 13. Thus, 10 as the seat, 7, is lowered after the wings, 9, have been elevated, the back rail, 4, is permitted a true vertical movement by being guided by means of the stems, 15, sliding within the bushings, 14. It will, therefore, 15 appear that the rear rail, 4, is movable between an upper and a lower position and in this way, the appearance of the rear portion of the bench is maintained uniform. It will also be noted that this rear rail, 4, 20 slides in a true vertical direction and does not assume an inclined position when at the upper end of its movement.

In order to cause the automatic elevation of these wings, 9, upon the movement of the seat, 7, to its elevated position, I have also mounted these wings, 9, so that they are slidably to a slight extent on their supporting rods, 8.

In addition, each of these supporting 30 wings is cut out as shown at 16 to permit the application of a torsion spring, 17, one end of which is rigidly secured to each of the support rods, 8, and the opposite end of each of which as is shown at 18 is made to engage 35 its respective wing to normally force the wings to their lowermost position.

Mounted on the outside face of each of the wings is a rod, 19, on which the sleeve, 20, is slidably mounted.

40 Each wing, 9, is additionally cut out on its inside face as is shown at 22 to accommodate this support rod structure and is also cut out a distance which enables the proper 45 sliding of the sleeve, 20, during the raising and lowering of the seat, 7, as will now be described.

Each sleeve, 20, has an upwardly projecting tongue, 21, into which one end of a rod, 23, is pivotally secured. The opposite end 50 of each of these rods is pivotally secured to the underside face of the seat, 7, as is shown at 24.

When the seat, 7, is in its lower horizontal position, each of the wings, 9, will be in the position indicated in Fig. 3.

60 Upon moving the seat about its hinges, each of these wings will be elevated to assume a vertical position because of their connection with the seat by means of the rods 23.

The length of the cut out portion, 22, is also such that when the seat, 7, has assumed a vertical position as shown in Fig. 2, the sleeves, 20, will have engaged the shoulders, 25, forming one end of the cut out portions, 22, and will also have moved these wings to their rearmost position of movement as is indicated in Fig. 2.

The inside back rail, 3, is provided adjacent each wing, 9 with a stop structure 75 shown at 26 which forms stalls into which the wings, 9, are moved when in their elevated position as has just been described.

These stops are provided in order to prevent the return of the wings to their horizontal position when it is attempted to lower the seat, 7, which movement would be caused by the torsion of the springs, 17.

However, before the seat, 7, has reached a lower upper inclined position, the sleeves, 80 20, will have engaged the shoulders, 25, formed by the cut out portions, 22, and will also have moved the wings to the position shown in Fig. 4 or to a position out of engagement with the stops, 26.

95 However, the seat will have been in engagement with the flat top side of each of the wings before this disengagement is effected and in this manner the wings will be prevented from dropping before the seat has assumed the position shown in Fig. 4.

In order to further guard against the lowering of the wings during the operation of lowering the seat, 7, I have notched out the inside face of the seat where it engages each 100 wing as is shown in dotted lines at 27 in Fig. 2 and from this it will follow that it is the notches 27 which first engage the wings, 9, at the fulcrum points 12 to prevent their dropping to horizontal position.

105 However, each of the wings has now been moved to a position out of engagement with the stops 26 and upon again elevating the lid, 7, to a position slightly higher than that indicated in the dotted lines in Fig. 2, the 110 springs 17 will automatically cause the lowering of these wings. In either position of the seat, the back rail, 4, will maintain a vertical position as has been described by means of a guide connection effected by the 115 stems, 15, and bushings, 14. The seat, 7, is prevented from excessive rearward movement and also positively connected with the rail, 3, by means of the metal band shown at 28 as being attached to the inside of the seat, 7, and as having a hook, 29, at its lower end. This band is slidable through a staple, 30, secured to the inside face of the stationary rail, 3, as is shown to be engaged by the hook, 29, when the seat has been elevated to 120 its vertical position.

125 From the foregoing description, taken in connection with the accompanying sheets of drawing, it will be apparent that I have provided a piano bench which may be very 130

readily adjusted so that its seat may assume either a lower horizontal or an upper inclined position.

Upon elevating the lid, 7, when the wings,

- 5 9, are in their horizontal positions, the connecting rods, 23, will cause an elevation of these wings, 9, against the tension of the springs, 17. Also, movement of the seat, 7, to a vertical position will cause these wings 10 to slide rearwardly to be engaged by the stops, 26, which prevent their return. Lowering of the seat, 7, will then cause it to fulcrum about the point 12 whereby the rear rail, 4, is moved vertically to assume its upper 15 position as is indicated in Fig. 4 and the seat will rest upon top inclined edges, 10 of the wings, 9. During the act of lowering seat, 7, each of the wings will be moved out of engagement with the stops, 26, but will be 20 prevented from falling under the influence of the spring 17, by being engaged with the under side of the seat, 7. However, a subsequent elevation of the seat, 7, to a position slightly higher than that indicated by the 25 dotted lines in Fig. 2 will permit these wings to drop by means of the springs 17. During this subsequent elevation of the seat, the rear rail, 4, will drop vertically because of its slidable connection with the rail, 3, and 30 if then the seat, 7, is again lowered, the latter will assume the position as indicated in Fig. 3.

It will thus appear that comparatively simple means are provided for accomplishing the objects of the invention. In addition, the structure is not complicated to such a degree as will render its operation uncertain.

What I claim, is:

- 40 1. A piano bench comprising a supporting body, a seat hingedly mounted in connection with said body to assume a lower or upper position, wings extending transversely across said body in coöperative relation with said seat and hingedly mounted to be engaged on their upper surfaces by said seat to cause its movement to its upper position, and means for automatically lowering said wings upon an elevating movement of said seat about its hinges.

45 2. A piano bench comprising a supporting body, a seat hingedly mounted in connection with said body to assume a lower or upper position, wings extending transversely across said body in coöperative relation with said seat and hingedly mounted to be engaged on their upper surfaces by said seat to cause its movement to its upper position, means for automatically so elevating said wings by movement of the seat about its hinges, and means for automatically lowering said wings by second elevating movement of said seat about its hinges.

- 50 3. A piano bench comprising a supporting body, a seat hingedly mounted in connection

with said body to assume a lower or upper position, wings extending transversely across said body in coöperative relation with said seat and hingedly mounted to be engaged on their upper surfaces by said seat to cause its movement to an upper position, means for locking said wings in such position until they are engaged by said seat during its lowering action, said wings being released after the seat is in its lowered position, and means for automatically so elevating and locking said wings by movement of the seat about its hinges.

4. A piano bench comprising a supporting body including front and back rails, a second back rail supported to be movable up and down, a seat, hinges supporting said seat from said second back rail, wings extending transversely across said body in coöperative relation with said seat and hingedly mounted so that when they are in elevated position, the seat will fulcrum and rest upon the wings to assume an upper position and carry said second back rail with it and means forming a part of the hinges for said seat for moving said second back rail in a true vertical direction when the seat engages the elevated wings.

5. A piano bench comprising a supporting body including front and back rails, a second back rail supported to be movable up and down, a seat, hinges supporting said seat from said second back rail, wings extending transversely across said body in coöperative relation with said seat and hingedly mounted so that when they are in elevated position, the seat will fulcrum and rest upon the wings to assume an upper position and carry said second back rail with it, said first named back rail having a series of sockets, a projection on the leaf of the hinges engaging said second back rail and overlapping said first named back rail when said sockets occur and downwardly projecting guide stems on said projections entering said sockets.

6. A piano bench comprising a supporting body, a seat hingedly mounted in connection with said body to assume a lower or upper position, wings extending transversely across said body in coöperative relation with said seat and hingedly mounted to be engaged on their upper surfaces by said seat to cause its movement to its upper position and means for automatically so elevating said wings by movement of the seat about its hinges.

7. A piano bench comprising a supporting body, a seat hingedly mounted in connection with said body to assume a lower or upper position, wings extending transversely across said body in coöperative relation with said seat and hingedly mounted to be engaged on their upper surfaces by said seat to cause its movement to its upper position,

said wings being also slideable transversely of said body, means for automatically elevating said wings by movement of said seat about its hinges, locking means for holding said wings elevated while the seat is elevated, said wings being slid out of their locking position during the act of lowering the hinged seat and spring means for auto-

matically lowering said wings upon again elevating said seat.

In testimony whereof I affix my signature in presence of two witnesses.

CHRISTIAN H. MARTIN.
